[57] CLAIM

The ornamental design for a mating clip for electric fence wire or the like, as shown and described.

DESCRIPTION

FIG. 1 is a top plan view of a mating clip for electric fence wire or the like showing my new design;

FIG. 2 is a bottom plan view thereof;

FIG. 3 is a side elevational view taken from the bottom of FIG. 1;

FIG. 4 is a side elevational view taken from the top of FIG. 1;

FIG. 5 is an end elevational view taken from the right of FIG. 1;

FIG. 6 is a perspective view thereof.

FIG.1
